RAILWAY TRAFFIC CONTROLLING
APPARATUSJohn M. Pelikan, Pittsburgh, Pa., assignor to The
Union Switch & Signal Company, Swissvale,
Pa., a corporation of Pennsylvania

Application March 31, 1938, Serial No. 199,236

6 Claims. (Cl. 246—34)

My invention relates to railway traffic controlling apparatus, and has for an object the provision of novel and improved apparatus for providing sensitive track circuits. A further object of my invention is the provision of means to check the integrity of the various elements of track circuits.

I shall describe two forms of apparatus embodying my invention, and shall then point out the novel features thereof in claims.

In the accompanying drawing, Fig. 1 is a diagram illustrating certain characteristics of an electron tube. Figs. 2 and 3 are diagrammatic views of two forms of apparatus each embodying my invention.

Similar reference characters refer to similar parts in each of the several views.

Referring to Fig. 1, the diagram constituting this view relates to a characteristic of an electron tube having a plate, a grid and a cathode. The diagram is plotted between grid voltage as abscissae and plate circuit current as ordinates, plate voltage being constant, and the diagram illustrates the relation between the grid voltage and plate current. For a given plate voltage, it will be noted that the plate current has its minimum value when the grid voltage has its maximum negative value, and as the negative grid voltage decreases toward zero voltage, the plate current increases. It is to be noted that the point of zero grid voltage is approximately on the upper end of the straight line portion of the performance curve of the tube. It is to be noted further that at certain values a slight change in the negative grid voltage causes a relatively large change in plate current.

Referring now to Fig. 2, the reference characters 1 and 1a designate the track rails of a stretch of railway track which are divided by means of the usual insulated rail joints 2 to form a track section D—E. Connected across the rails at one end of the section is a suitable source of current, such as track battery 3.

The reference character T designates an electron tube which, as here shown, comprises a heating filament 4, a cathode 5, a grid 6 and a plate 7. The heating element 4 is constantly heated by current from a secondary winding 8 of a transformer J, a primary winding 9 of transformer J being connected to a suitable source of alternating current, such as a generator, not shown.

A direct current relay TR is controlled by tube T, the relay TR being interposed in a plate circuit for tube T, which circuit may be traced from

terminal B of a suitable source of current, such as a battery, not shown, through the winding of relay TR, primary winding 10 of a transformer J1 to be referred to later, plate 7, intervening tube space to cathode 5 of tube T and terminal C of the source of current. The plate circuit for tube T is controlled by the grid circuit for the tube. This grid circuit passes from the negative terminal of battery 3, through rail 1 to the negative terminal of a suitable source of current, such as battery 12, the positive terminal of battery 12, cathode 5, tube space to grid 6, secondary winding 13 of a transformer J2, to be referred to later, and rail 1a to the positive terminal of battery 3. It is to be noted that the batteries 3 and 12 are included in the grid circuit in a manner such that the electromotive force of battery 3 opposes the electromotive force of battery 12. A resistor R is preferably connected across the grid and cathode of tube T.

A primary winding 14 of the transformer J2 is connected to a secondary winding 15 of transformer J. A secondary winding 11 of transformer J1 is connected with the winding of a relay TC; included in the circuit for relay TC is an asymmetric unit 16, such as is used to permit a direct current relay to be energized by an alternating current source.

A control apparatus circuit passes from terminal B through front contact 17 of relay TR and front contact 18 of relay TC to the control apparatus. As the form of the control apparatus forms no part of my present invention, it is illustrated conventionally on the drawing.

The parts are so proportioned that, with the track section D—E unoccupied, the electromotive forces of batteries 3 and 12 substantially balance and the steady voltage of grid 6 is approximately zero voltage, with the result that the direct current component of the plate circuit current is relatively large and the relay TR is energized sufficiently to pick up, closing front contact 17.

The transformer J2 superimposes an alternating electromotive force on the grid circuit which causes the voltage of grid 6 to be alternately positive and negative in step with the alternating voltage induced in the secondary winding 13 of transformer J2. This alternating grid voltage produces an alternating current component of the plate circuit current which in turn induces in the secondary winding 11 of transformer J1 an alternating electromotive force that, when rectified by the asymmetric unit 16, effectively energizes the relay TC. The parts are further so proportioned that under this normal condition (track section

D—E unoccupied) the direct current component of the plate circuit current effectively energizes relay TR and the alternating current component effectively energizes relay TC.

- 5 When a train enters the track section D—E, the wheels and axles of the train shunt battery 3 so that the grid 6 has a steady negative grid voltage substantially equal to the voltage of battery 12. The parts are so proportioned that the steady 10 negative grid voltage impressed upon grid 6 of tube T when a train shunts the track battery 3 reduces the direct current component of the plate circuit current to such a low value that the relay TR is deenergized to a point below its release value 15 and the relay is released, opening front contact 17 interposed in the control circuit. It should be noted that the alternating current component of the plate circuit current may under this steady negative grid voltage condition be insufficient to 20 effectively energize relay TC but operation of relay TC at this time is immaterial.

Then, when the train vacates track section D—E, the shunt path around battery 3 is removed and the steady grid voltage again becomes 25 of the order such that the direct current component of the plate current is sufficient to energize relay TR; relay TR becomes energized and closes front contact 17 to complete the circuit for the control apparatus.

30 The relay TC acts as a tube integrity check relay. That is to say, relay TC will only become energized if the alternating voltage current superimposed upon the steady voltage of the grid circuit is amplified by the action of the tube T. In 35 the event a short circuit is established across the grid and plate, or plate and cathode, and the tube can no longer act as an amplifier, the alternating current superimposed upon the grid circuit is no longer reproduced in kind on the plate 40 circuit, so that relay TC becomes deenergized and opens front contact 18 to open the circuits for the control apparatus.

Also, since the alternating current superimposed on the grid circuit passes through the 45 various elements of the grid circuit, this superimposed alternating current acts as a check upon the condition of the grid circuit. That is to say, in the event of a broken rail or a broken wire in the grid circuit, the grid 6 would no longer be supplied with this alternating current, and the alternating current would no longer be amplified and reproduced in kind on the plate circuit, so that relay TC would become released and open contact 18 to open the control apparatus circuit.

55 Referring now to Fig. 3, the apparatus of Fig. 2 is modified so as to provide an alternating current track circuit for track section D—E, and to provide alternating current sources for the grid and plate circuits for tube T. The alternating 60 current track circuit is established by connecting a secondary winding 19 of a track transformer J3 across the track rails at one end of the section, a primary winding 20 of transformer J3 being connected to a suitable source of alternating current, 65 such as a generator not shown, and by connecting a primary winding 21 of a transformer J4 across the rails at the other end of the section. Transformer J4 may be a step-up transformer, that is, a transformer in which the voltage in the 70 secondary winding is relatively high in relation to the voltage in the primary winding.

A rectifying unit RU1 is connected to a secondary winding 22 of transformer J4, that is to say, the left-hand terminal of secondary winding 22 75 of transformer J4, as viewed in Fig. 3, is con-

nected to input terminal 23 of rectifying unit RU1, and the right-hand terminal of secondary 5 22 is connected to input terminal 24 of unit RU1. A second rectifying unit RU2 is connected to a secondary winding 27 of transformer J so that the upper terminal of winding 27, as viewed in Fig. 3, is connected to input terminal 28 of unit RU2, and the lower terminal of winding 27 is connected to the input terminal 29 of unit RU2.

The grid circuit for tube T may now be traced 10 from positive output terminal 25 of unit RU1 through secondary winding 13 of transformer J3, grid 6, intervening tube space to cathode 5 of tube T, positive output terminal 30 of unit RU2, negative output terminal 31 of unit RU2, and to 15 negative output terminal 26 of unit RU1. It is to be noted that rectifying units RU1 and RU2 are included in the grid circuit for tube T in such a manner that the electromotive force of unit RU1 is opposed by the electromotive force of unit RU2. A resistor R1 is preferably connected across grid 6 and cathode 5.

A rectifying unit RU3 is connected with a secondary winding 32 of transformer J so that the upper terminal of winding 32, as viewed in Fig. 3, 25 is connected to input terminal 33 of unit RU3, and the lower terminal of winding 32 is connected to input terminal 34 of unit RU3. The plate circuit for tube T may now be traced from positive output terminal 35 of unit RU3 through inductance 37, with capacitance 38 in multiple with a portion of the inductance 37 and capacitance 39 in multiple with the remainder of inductance 37, the winding of relay TR, primary 10 of transformer J1, plate 7, intervening tube space to 35 cathode 5 and to the negative output terminal 36 of rectifying unit RU3.

It is to be noted that inductance 37, which has in multiple with it capacitances 38 and 39, is included in the plate circuit for tube T so that 40 the pulsating current resulting from the action of rectifying unit RU3 may be smoothed out.

Under the normal condition of the apparatus, that is, track section D—E unoccupied, the electromotive force derived from the track circuit 45 through transformer J4 and rectifying unit RU1 opposes the electromotive force derived from rectifying unit RU2 with the result that the steady grid voltage is substantially zero and the direct current component of the plate circuit current is 50 sufficient to energize relay TR at the desired value. The alternating voltage impressed on grid 6 by virtue of transformer J2 is such as to produce an alternating current component of the plate circuit current such as to effectively energize relay 55 TC to check the operating condition of tube T. It should be pointed out that the electromotive force derived from transformer J2 is effective to impress an alternating voltage on the grid 6 through the individual elements of the units RU1 60 and RU2 in their non-conducting direction. By the use of transformer J4 a relatively high track circuit voltage can be obtained for balancing with the local biasing voltage derived from unit RU2 so that the proportioning of the parts is not 65 critical.

When a train enters the section D—E of Fig. 3 and shunts the track rails, the electromotive force of unit RU1 is reduced to nearly zero and the steady grid voltage is that effected by unit RU2 70 which is a negative voltage. This negative grid voltage reduces the direct current component of the plate circuit current to a value where relay TR is released, opening front contact 17 of the control circuit.

When the train vacates section D—E of Fig. 3, the wheels and axles of the train no longer shunt the track rails so that the electromotive force derived from unit RU1 again opposes the electromotive force derived from unit RU2 with the result that the steady grid voltage is substantially zero; relay TR is energized by virtue of the direct current component of the plate current; and the apparatus is in its normal condition.

One advantage of apparatus embodying my invention is the provision of means whereby a slight change, which in itself is not of an order sufficient to control a track relay, in track circuit voltage may be amplified so as to control a track relay. Hence, since a slight change in track circuit voltage is effective to control the track relay, it can be seen that the voltage applied across the track rails need be varied by only a slight degree, and, therefore, a very sensitive track circuit is provided. A further advantage of my invention is the provision of means for checking the integrity of the elements of the grid circuit and of the electron tube.

Although I have herein shown and described only two forms of railway track circuit apparatus embodying my invention, it is understood that various changes and modifications may be made therein within the scope of the appended claims without departing from the spirit and scope of my invention.

Having thus described my invention, what I claim is:

1. In combination, a section of railway track; an electron tube having a plate, a grid and a cathode; a first source of current connected across the rails at one end of the section, circuit means to connect said grid and cathode of said tube across the rails at the other end of the section, a second source of current interposed in said circuit means and disposed to oppose the electromotive force of said first source, a plate circuit responsive to the equilibrium of electromotive force of said first and second sources, a first relay responsive to said plate circuit, a third source of current impressed across said grid and cathode of said tube, and a checking relay controlled by the plate circuit responsive to electromotive force of said third source of current.

2. In combination, a section of railway track; an electron tube having a plate, a grid and a cathode; a first source of electromotive force connected across the rails at one end of the section, circuit means to connect said grid and cathode of said tube across the rails at the other end of the section, a second source of electromotive force interposed in said circuit means and disposed to oppose the electromotive force of said first source to provide a steady biasing grid voltage, a plate circuit responsive to the balancing of the electromotive forces of said first and second sources, a first relay controlled by the plate circuit and responsive to such biasing grid voltage, an alternating grid voltage provided by a third source of electromotive force connected across said grid and cathode of said tube, and a second relay controlled by the plate circuit and responsive to said alternating grid voltage.

3. In combination, a stretch of railway track provided with a first source of electromotive force connected across the track rails thereof, an electron tube having a plate and a grid and a cathode, a circuit including said track rails for applying said first source of electromotive force across the grid and cathode of said tube whereby

the conductivity of said tube is rendered responsive to traffic conditions on said stretch of track, means for impressing a second source of electromotive force across the grid and cathode of said tube, a plate circuit for said tube including a source of current, control means responsive to the current flowing in said plate circuit as affected by said first source of electromotive force, and checking means responsive to the current flowing in said plate circuit as affected by said second source of electromotive force.

4. In combination, a stretch of railway track provided with a first source of electromotive force connected across the track rails thereof, an electron tube having a plate and a grid and a cathode, a circuit including said track rails for applying said first source of electromotive force across the grid and cathode of said tube whereby the conductivity of said tube is rendered responsive to traffic conditions on said stretch of track, means for applying a source of alternating electromotive force across the grid and cathode of said tube, a plate circuit for said tube including a source of current, control means interposed in said plate circuit responsive to the current flowing in said plate circuit as affected by said first source of electromotive force, and checking means inductively coupled with said plate circuit and responsive to the current flowing in said plate circuit as affected by said source of alternating electromotive force.

5. In combination, a stretch of railway track provided with a first source of electromotive force connected across the track rails thereof, an electron tube having a plate and a grid and a cathode, a circuit including said track rails for applying said first source of electromotive force across the grid and cathode of said tube whereby the conductivity of said tube is rendered responsive to traffic conditions on said stretch of track, means for applying a source of alternating electromotive force across the grid and cathode of said tube, a plate circuit for said tube including a source of current, control means responsive to the direct current component of the current flowing in said plate circuit as affected by said first source of electromotive force, and checking means responsive to the alternating current component of the current flowing in said plate circuit as affected by said source of alternating electromotive force.

6. In combination, a stretch of railway track provided with a first source of alternating electromotive force connected across the rails thereof, an electron tube having a plate and a grid and a cathode, circuit means including said track rails for inductively coupling said first source of alternating electromotive force across the grid and cathode of said tube, a rectifier interposed in said circuit means for rectifying the current flowing therein into unidirectional current, a second source of alternating electromotive force, means for applying said second source of alternating electromotive force across the grid and cathode of said tube, a plate circuit for said tube including a source of current, control means responsive to the current flowing in said plate circuit as affected by said first source of alternating electromotive force, and checking means responsive to the current flowing in said plate circuit as affected by said second source of alternating electromotive force.

JOHN M. PELIKAN.
